(57) **CLAIM**

The ornamental design for a food holder for use in vehicles, as shown and described.

DESCRIPTION

FIG. 1 is a perspective view of a food holder showing my design taken from above and from the left and front, with the environment in which the food holder is used being shown in dotted outline;

FIG. 2 is a perspective view of the food holder of FIG. 1, shown alone;

FIG. 3 is a perspective view of the food holder taken from below and from the right and rear;

FIG. 4 is a left end view thereof, a right hand end view being a mirror image thereof;

FIG. 5 is a front view;

FIG. 6 is a rear view;

FIG. 7 is a top view; and,

FIG. 8 is a bottom view.
